(57) **CLAIM**

The ornamental design for a body pad, as shown and described.

DESCRIPTION

FIG. 1 illustrates a front perspective view of a body pad; FIG. 2 illustrates a front view of the body pad thereof; FIG. 3 illustrates a back view of the body pad thereof; FIG. 4 illustrates a left side view of the body pad thereof; FIG. 5 illustrates a right side view of the body pad thereof; FIG. 6 illustrates a top view of the body pad thereof; FIG. 7 illustrates a bottom view of the body pad thereof; FIG. 8 illustrates a back perspective view of the body pad thereof; and, FIG. 9 illustrates an exploded view of the body pad thereof. The broken lines shown in the Figures illustrate portions of the body pad that form no part of the claimed design.
